UNITED STATES PATENT OFFICE.

SAMUEL E. PELPHREY, OF FRENCH, NEW MEXICO.

DEVICE FOR MASSAGING AND LUBRICATING THE HUMAN SYSTEM.

Application filed April 15, 1926. Serial No. 102,263.

This invention relates to a device for massaging and lubricating the rectum and the prostate gland of the human system.

An object of the invention is to provide 5 a simple and efficient device for lubricating the rectum and the prostate gland of the human system for the purpose of keeping them elastic, clean and well lubricated, and to avoid the injurious effects of constipation. 10 A further object is to provide a device which when inserted can be manipulated to massage the parts with which it comes in contact and thereby cause stimulation of that part and neighboring organs.

15 The invention is illustrated in the drawings of which—

Figure 1 is a side elevation;

Figure 2 is a horizontal longitudinal section;

20 Figure 3 is a vertical longitudinal section;

Figure 4 is a partial section through the rear end of a modified form of the device;

25 Figure 5 is a partial section through the front end of a modified form of the device.

30 The form of the invention shown in the drawings is a preferred form, although it is understood that modifications in the construction and arrangement of the parts, and in the character of the material used may be adopted without departing from the spirit of the invention as set forth in the appended claims.

35 In its general aspect the invention comprises a body portion, preferably of rubber, either hard or soft, or any other equivalent material, which has a rear body portion forming a chamber or reservoir for any suitable liquid, preferably lubricating oil, suitable for introduction into the human system 40 through the rectum for the purpose of massaging the same and the prostate gland. The forward portion of the device is preferably narrower, a curved tubular member having a passage therein through which a lubricating oil may pass. The front end of the forward portion is provided with a round head which facilitates the introduction of the instrument into the body and 45 also permits of a ready manipulation of it for the purpose of massaging the walls of the colon. By having the forward or massaging portion curved this effect is more readily obtained than if these portions were straight.

50 The rear portion of the device is provided with a cap which may be screwed or other-

wise removably fastened to the main body portion so that a quantity of liquid can be readily disposed in the reservoir. The end of this cap may be formed of stiff or resilient material as desired.

55 The device may be made integral in one piece or it may be made in separate sections.

60 In the preferred form of the invention 10 is a body portion having a chamber 11. To 65 the front of this body portion is connected a tubular massage element 12 having a narrow bore 13 and a rounded head portion 14. At the rear of the body portion, which is 70 preferably screw threaded as at 15, is a cap 70 16 adapted to be screwed on to the end. This cap may have a solid wall 17 at its end or it may have a flexible wall such as 18 (see Figure 4) of any suitable material such as 75 flexible steel, so that this flexible wall can be pressed inward to facilitate the forcing of the lubricating material within the device into the system.

80 As shown in Figure 5 the tubular massage element 20 is made separate from the body portion and screw-threaded into the front portion thereof. The front end of the body portion is provided with an enlarged flange 19 which, lying at the end of the major element 12, will more or less limit the extent 85 to which the device can be inserted into the body. By having the tubular massage element 12 curved it is very easy, after the device is inserted into the rectum, to turn it 90 around, moving it backward and forward while turning it, in order to massage the walls of the rectum, thereby stimulating those walls and making them elastic, at the same time lubricating them and cleaning them. This massage is also effective in its 95 action on the prostate gland.

100 Any desired lubricating liquid or fluid can be placed within the device and as the parts are massaged and become heated in addition to their natural heat the liquid will readily flow out on to the walls thereof.

What I claim is:

1. A massage device which comprises a body portion having an enlarged chamber having a flange at its forward end and forming a reservoir for a lubricating liquid, a removable cap on the rear end of said body portion, and a curved tubular massage element connected with the forward end of the body portion.

105 2. A massage device which comprises a body portion having an enlarged chamber

forming a reservoir for a lubricating liquid, the rear end of the body being externally screw threaded, an internally screw threaded cap screwing on the said rear end of the body portion, and a curved tubular massage element connected with the forward end of the body portion, the forward end of the massage element having a rounded head thereon.

10 3. A massage device which comprises a body portion having an enlarged chamber forming a reservoir for a lubricating liquid, a removable cap screwing on the rear end of said body portion, the end wall of the

cap being flexible and a curved tubular massage element connected with the forward end of the body portion, the forward end of the massage element having a rounded head thereon, the forward end of the body portion having an enlarged flange thereon. 15 20

4. A massage device which comprises a body portion having a reservoir, a removable cap secured on the rear end thereof, the end wall of the cap being flexible, and a curved tubular massage element connected 25 to the forward end of the body portion.

SAMUEL E. PELPHREY.
